LEVI HEYWOOD, OF GARDNER, MASSACHUSETTS.

Letters Patent No. 79,976, dated July 14, 1868.

IMPROVEMENT IN MACHINES FOR SHAVING RATTAN.

The Schedule referred to in these Letters Patent and making part of the same.

TO ALL WHOM IT MAY CONCERN:

Be it known that I, LEVI HEYWOOD, of Gardner, in the county of Worcester, and State of Massachusetts, have invented certain Improvements in Machines for Shaving Rattan, of which the following is a full, clear, and exact description, reference being had to the accompanying drawings, making part of this specification, in which—

Figure 1 is a front elevation of my improved machine.

Figure 2 is an elevation of one side of the same.

Figure 3 is an elevation of its opposite side.

Figure 4 is a vertical section on the line $z z$ of fig. 1.

Figure 5 is a transverse section on the line $y y$ of figs. 2 and 4.

Figure 6 is a transverse section on the line $z z$ of figs. 2 and 4.

Figures 7, 8, and 9, details to be referred to.

The object of my invention is to reduce rattan to a uniform thickness and width after having been split into strips; and my invention consists in a knife or scraper for planing down or removing the portion of the joint of the rattan after having been cut into strips; and my invention also consists in one or more knives for shaving the strip on the inner side, next to the pith, in combination with a pair of knives against which the edges of the strip are brought in contact as it is fed along, after having been shaved on its under side, by which means the joint is first removed, and the strip is then reduced to the uniform thickness and width desired.

To enable others skilled in the art to understand and use my invention, I will proceed to describe the manner in which I have carried it out.

In the said drawings, A is the framework in suitable bearings, in which revolves the shaft B, one of its extremities being provided with a drum, C, over which runs the belt which communicates power thereto from the driving-shaft, (not shown.)

The portion of the shaft B within the sides $a a$ of the framework is provided with two circular flanges, $b b$, to be described hereafter, (see fig. 5;) and the extremity of the shaft B, opposite the drum C, has secured thereto a cog-wheel, D, which drives a corresponding wheel, E, on the extremity of a shaft, F, also provided with two circular flanges, $c c$, similar to those $b b$. G G' G'' G''' are studs projecting from the framework, the outer extremities of the studs being provided with gear, H H' H'' H''', corresponding to those D and E.

I I' I'' I''' are a series of smooth rolls, which are revolved by the gear H H' H'' H'''. The centre of each of the rolls I I'' is placed in the same vertical plane, and directly over the edge of a knife, d, (see figs. 4 and 7,) which is placed transversely, and is made adjustable upon its stock or block J by means of a screw, e, fig. 7, passing through a slot, f, in each end, by which construction the knife may be readily removed, and replaced after being sharpened.

K K are cam-shaped levers pivoted, at 10, to the framework, one lever being employed at each end of the transverse knives d d, to clamp them firmly in place when adjusted laterally in their slots f f.

The ends of each of the blocks J, with its knife d secured thereto, rest in slots g g, formed for their reception in the sides $a a$; and the blocks are raised or lowered by operating screws h, in order to regulate the space between the bottom of each roll I I'' and the knife-edge under it, and consequently the thickness of the shaving to be removed from the strip. The alternate rolls I' I''' are placed in bearings in the framework, so that their centres will be directly over the centres of rolls L L', of corresponding form and size, the rolls I' L and I'' L' constituting two pair of feed-rolls, by and between which the strip of split rattan is carried against the transverse knives d d. The two upper feed-rolls, I' and I''', and the upper flange-roll or shaft, F, are free to be pressed upward by the entrance of strips of varying thickness against the resistance of rubber springs i, which allow the said rolls to yield as required, the degree of downward pressure being regulated by the screws k k.

M M are separate and independent knives, of the form shown in figs. 1, 4, and 9, which rest against the inclined portion 11 of the front of the framework, and are moved up and down thereon within guides l l, screwed thereto at m, by mechanism now to be described.

In the top of the inclined front portion of the framework are formed slots *n n*, for the reception of pins *o o* projecting from the backs of the tops of the knives *M M*. *p p* are spiral springs, the upper ends of which are secured to the pins *o o*, while their lower ends are secured to studs *r r*, projecting from the inside of the inclined portion of the framework, the springs serving to constantly keep the knives *M M* down upon the strip of rattan, as seen in fig. 4, until relieved to enter new strips, by operating the handles of levers *N N*, pivoted, at *s s*, to the front of the framework, the inner ends of each of these levers being provided with a slot, *12*, to fit over a pin, *13*, screwed in the top of each knife.

O O are guides through which the split rattan passes, said guides being screwed, at *14*, to the framework, just in advance of the edges of the knives *M M*.

P P P, &c., are also guides placed in pairs between two consecutive rolls *I I' I'' I'''* and the flanged roll or shaft *F*.

The strips of split rattan are first passed through apertures in the guides *O O*, when the knives *M M* are raised by bringing down the handles of the levers *N N*, to allow of the strips being entered under them, after which the knife-edges are brought down upon the strips by the resistance of the springs *p p*, and as the feed-rolls carry along the strips, the portions of the joints of the rattan thereon are planed down or scraped off smooth, as required.

After passing through the first pair of feed-rolls, *I''' L*, the strips are conducted through guides *P P*, and between the presser-roll *I''* and the edge of the first transverse knife, *d*, the roll being provided with yielding bearings, to allow the strips, as they pass under, to raise them, to insure the planing off of a thin shaving from the under or pith-side of the rattan.

The strips now pass between the next guides, *P P*, and thence through the next pair of feed-rolls, *I' L*, after which they are guided between the presser-roll *I* and edge of the next transverse knife, *d*, which is carefully adjusted to bring its edge in a position, with respect to the bottom of the roll *I*, to insure the taking off of another thin shaving from the lower or pith-side of the strip, thus reducing it to the thickness required.

After passing through another pair of guides *P P*, the strips are carried between the circular flanges *b b* and *c c* of the shafts *B* and *F*, and are conducted against the edges of a couple of pair of knives, *R R*, fig. 8, one of each pair of which is placed on each side of and close to the surface of the flanges, by which means the edges of the strips are cut down and brought to a uniform width throughout their length.

The edges of the knives *R R* are adjusted in their proper position, relatively to the flanges *b b c c*, by supporting their blades in slotted bars *t t*, extending down vertically through a plate, *S*, attached to the rear of the framework, the slotted bars being secured in place by screws, *15*, the lower end of each bar *t* being also provided with a screw, *16*, which may be turned in either direction, to raise or lower the heel of the knife, and thus give the blade the inclination desired.

In the foregoing description, I have spoken of two knives *M M*, and two pairs of knives *R R*, but it is evident I may use only one knife *M*, and but one pair of knives *R R*, or I may use any number of knives *M M*, and a corresponding number of pairs of knives *R R*, if desired, without departing from the spirit of my invention.

In reducing the strip to the required thickness, I prefer to employ more than one transverse knife *d*, as it is easier to plane off more than one thin shaving than a single thick one, the strip being thereby passed more rapidly through the machine, and the thin shavings are more valuable than thick shavings for upholstering purposes.

Claim.

What I claim as my invention, and desire to secure by Letters Patent, is—

The arrangement of the knife *M*, constructed and operated substantially as described.

I also claim the arrangement of the knives *d*, in combination with the presser-rolls *I I''* and operating-screws *h*, all constructed and operating substantially as set forth and for the purpose stated.

LEVI HEYWOOD.
